UNITED STATES PATENT OFFICE.

MAX J. PALM, JR., OF CINCINNATI, OHIO.

DESIGN FOR A PLATE OR SIMILAR ARTICLE.

Application filed August 27, 1928. Serial No. 27,967. Term of patent 3½ years.

To all whom it may concern:

Be it known that I, MAX J. PALM, JR., a citizen of the United States of America, and a resident of Cincinnati, in the county of Hamilton and State of Ohio, have invented a new, original, and ornamental Design for a Plate or Similar Article, of which the following is a specification, reference being made to the accompanying drawing, forming part

The figure is a plan view of a plate, showing my new design, the plate being shown partially broken away at the right and left hand margins. Only a portion of the ornamentation is shown but it is understood that the remainder is a mere repeat thereof.

I claim:

The ornamental design for a plate or similar article, as shown and described.

MAX J. PALM, JR.
